CLAIM

The ornamental design for a pneumatic compression device, as shown and described.

DESCRIPTION

FIG. 1 is a perspective view of a pneumatic compression device showing the claimed design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is top plan view thereof; and,

FIG. 7 is a bottom plan view thereof.

The broken lines in the figures show portions of the pneumatic compression device that form no part of the claimed design.
